UNITED STATES PATENT OFFICE

THEODORE KOCHANKOFF, OF BROOKLYN, NEW YORK

DESIGN FOR A FINGER RING

Application filed April 7, 1932. Serial No. 43,414. Term of patent 14 years.

To all whom it may concern:

Be it known that I, THEODORE KOCHANKOFF, a citizen of the United States, residing in the city of Brooklyn, county of Kings, and State of New York, have invented a new, original, and ornamental Design for Finger Rings, of which the following is a specification.

In the accompanying drawing, forming part of this specification—

What I claim is:

The ornamental design for a finger ring, as shown.

In testimony whereof I hereunto affix my signature.

THEODORE KOCHANKOFF.
